UNITED STATES PATENT OFFICE.

JOHN STEMBER, OF NEW YORK, N. Y.

DESIGN FOR A BODY PORTION FOR BELTS.

SPECIFICATION forming part of Design No. 32,806, dated June 5, 1900.

Application filed May 10, 1900. Serial No. 16,230. Term of patent 3½ years.

To all whom it may concern:

Be it known that I, JOHN STEMBER, a citizen of the United States, residing at New York, in the borough of Manhattan and State 5 of New York, have invented and produced a new and original Design for Body Portions for Belts, of which the following is a specification, reference being had to the accompanying drawings, forming part thereof.

10 Figure 1 is an elevation of a body portion of a belt, showing my new design; and Fig. 2 is a transverse section thereof, taken on the line 2 2 of Fig. 1.

As shown in the drawing, the leading or 15 material feature of my design consists of a central ornament A, simulating two crossed figure eights, on both sides of which are lon-

gitudinal loop-shaped ornaments B. The loop-shaped ornaments B converge toward their ends and are crossed by volute portions 20 C, which simulate knots formed in the loops. The central ornament A and the loops B are embossed in the body portion of the belt and resemble the appearance of rope.

What I claim is—

25 The design for a body portion for belts as herein shown and described.

In testimony that I claim the foregoing as my invention I have signed my name in presence of two subscribing witnesses.

JOHN STEMBER.

Witnesses:

M. H. WURTZEL,
GEO. L. WHEELOCK.
